Fig. 1

Fig. 2

Fig. 3

Fig. 4

FIGURE 1 is a side elevation of a bank showing my new design;

FIG. 2 is a top plan view;

FIG. 3 is a front elevation;

FIG. 4 is a rear elevation; and

FIG. 5 is a reduced bottom plan view of the bank shown in FIG. 1.

The characteristic feature of my design resides in the combination on the bank disclosed of the integrally molded front ornamental plate-effect of substantial thickness connected to the crown portion by a web having a coin-receiving slot in the upper edge thereof, all as shown.

I claim:

The ornamental design for a bank, as shown and described.
